UNITED STATES PATENT OFFICE.

ADOLPH WILLIAM GAST, OF CHICAGO, ILLINOIS, ASSIGNOR TO CHICAGO MINIATURE LAMP WORKS, OF CHICAGO, ILLINOIS, A CORPORATION OF ILLINOIS.

ELECTRIC-SIGN STRUCTURE.

1,169,254.

Specification of Letters Patent. Patented Jan. 25, 1916.

Application filed October 10, 1911. Serial No. 653,859.

To all whom it may concern:

Be it known that I, ADOLPH W. GAST, a citizen of the United States, residing at Chicago, in the county of Cook and State of Illinois, have invented certain new and useful Improvements in Electric-Sign Structures; and I do hereby declare the following to be a full, clear, and exact description of the invention, such as will enable others skilled in the art to which it appertains to make and use the same.

This invention relates to improvements in electrically illuminated sign structures and consists of the matters hereinafter described and more particularly pointed out in the appended claims.

The primary object of the invention is to provide a sign structure including a plurality of electrically illuminated letters or designs and when required, one or more suitable spacing blocks, and a supporting member, each letter, design or spacing block constituting a unit, and each unit being not only removably engaged on said supporting member but being separably engaged with the adjacent units on said supporting member. The several units have their bases so constructed with reference to the supporting member that when said bases are engaged with said supporting member the letters or designs on said bases will assume the desired, (usually upright) position, and when spacing block units are required, the necessary spaced relation between the letters or designs of said units.

Another object of the invention is to provide a base for units of the kind described, that is to say letters, designs, or spacing blocks, which consists of two or more parts 40 of insulating material to one of which the letter or design of the unit is fixed and in the adjacent faces of which are provided passageways to receive the electric conductors. The bases of the units are made of 45 such lengths as to properly space the letters, designs and the like, and are severally provided with sockets at one end and with projecting tongues at the other end whereby the bases may be held in assembled relation and 50 the conductors therein in proper electrical connection.

In the accompanying drawings: Figure 1 is a perspective view of an embodiment of the invention shown assembled. Fig. 2 is 55 a section through Fig. 1 approximately on

the line 2—2. Fig. 3 is a section through Fig. 2 approximately on line 3—3. Fig. 4 is a section through Fig. 2 on the line 4—4. Fig. 5 is a detail fragmentary perspective view of a letter and base, the parts 60 of the base being shown separated for the purpose of illustration. Fig. 6 is a detail perspective view of one of the conductors arranged in each of the bases and each of the spacing blocks. Fig. 7 is a fragmentary 65 sectional view through Fig. 5 on line 7—7. Fig. 8 is a section through Fig. 5 on line 8—8.

The present invention embraces generally a structure embodying a plurality of 70 lamp and letter units, each formed with a base, preferably rectangular, and having connectors therein, and a supporting structure in the form of a channeled member, the connectors of one unit engaging the connectors of an adjacent unit. 75

Referring now to that embodiment of my invention illustrated in the accompanying drawings, 1 indicates a supporting member for the series of units comprising the sign 80 structure. In the drawing there are shown only two letters, namely, H and I, but it will be evident that as many letters may be used as may be desired, and any arrangement thereof may be had as occasion may demand. Each letter is mounted on a base, the two together constituting a unit.

2 indicates the base of the letter H and 3 the base of the letter I. Each base is of such length as to provide equal extensions 90 of the base at each side of each letter, so that when the units are assembled, the letters will all be equally spaced apart. The support 1 is, as shown, in the form of a trough and of such cross-section as to receive and retain the bases. The bases are of identical construction and each comprises, as shown herein, upper and lower plates or blocks 4 and 5, respectively, of insulating material, such as porcelain or the like (see 100 Fig. 5). To the upper plate 4 is attached the letter, character or design. Where the letter has more than one bottom end, as for example, in the case of the letter H, one of said ends is mounted in a recess or depression formed in the top of the upper plate 4, as shown in Fig. 7. The other end rests on the top surface of said plate 4 and if desired may be cemented thereto. 105

6 and 7 indicate current supply wires for 110

the letter. Said wires extend through suitable vertical passageways formed in the upper plate 4 in line with and opening into the depression or recess on the top of said plate. The said passageways are filled with plaster of Paris or other suitable material which merges with a conductor protecting member 8 provided on the back of the letter.

The construction disclosed in Figs. 7 and 10 8 is important as the same not only provides means for accommodating the wires 6 and 7, but also provides means by which the letter is anchored to the plate 4. The anchored end of the letter has a depending 15 lug 14' with laterally extending ears 14" which are firmly secured in the plaster of Paris or other cement filling 4' in the recess or depression in the plate 4. If desired, suitable sockets 4" may be provided 20 in the side walls of the recess or depression in the top of the plate for positively holding the cement 4' in place and preventing relative movement between the letter and base. It will also be observed that by the 25 arrangement of the cement filling 4' described and of the protecting member 8 on the back of the letter, said letter is firmly braced in position, as the protecting member 8 merges with and forms part of the filling 30 4' so that the same acts to protect and enclose the wires 6 and 7 and at the same time forms a brace and retaining means for the letter.

The wires 6 and 7 are connected to current 35 conducting members 11 and 12 respectively which consist of flat, narrow parallel strips located in longitudinal grooves or channels 15 and 16 formed in the top of the lower plate 5 of the base. The wire 6 is connected to the current conducting member 11 by means of a nut and screw 9 and 10 which also serve to secure the said conducting member 11 in its channel. A nut and screw 13 and 14 perform like functions in 40 connection with the wire 7 and the conducting member 12.

The conducting members 11 and 12 extend substantially the length of the plates 4 and 5 and in addition project beyond said 50 plates forming the base at one end to provide tongues or plugs 17 and 18. The opposite ends of said conducting members are bent downwardly into depressions 19 formed in the bottoms of the grooves or channels 55 15 and 16. The bent down ends of said conducting members 11 and 12 coact with short bent conducting strips 20 and 21 to form sockets 22 and 23 adapted to receive the plugs or tongues 17 and 18 of the adjacent unit. Said short strips 20 and 21 are secured in place by screws and nuts 24 and 25 which also serve to attach the conducting members 11 and 12 to the lower plate 5 of the base. The upper plate 4 has on its bottom side a depending rib 26 which fits be-

tween the outer walls 28, 29 of the channels or grooves 15, 16 and bears upon the intermediate wall 27 separating said channels or grooves, which intermediate wall as shown (see Fig. 4) is of less height than said outer 70 walls. The upper and lower plates are attached together by a bolt and nut 30, 31, the nut being preferably countersunk in the top of the upper plate as indicated at 32.

33 indicates a spacing block adapted to be 75 used to separate the letters into words or to separate the individual letters, designs or other characters. Any number of such spacing blocks may be provided as required. Said spacing block consists simply of a base as heretofore described without the attached letter and without the depression or recess and wires 6 and 7 required in the case of the letter-base. In addition to the spacing block, I provide an end block 34. 80 This block is similar in construction to the spacing block 33 but while it has sockets 22', 23', like the sockets 22, 23, it has no tongues like the tongues 17 and 18. Instead of said tongues, line wires 35, 36 are attached to the 85 conducting members of said end block by bolts and nuts 37, 38. Said wires extend through a sleeve 39 of insulating material fixed in a plate 34^a forming the end wall of the channel support 1, screws 41, 41, securing said plate in proper position. A thumb screw 40 retains said bushing in said end plate. When assembling the sign structure, the end block 34 is placed in the left hand end of the supporting member 1 adjacent 90 the end plate 34^a and is rigidly held therein by any desired means, as, for instance, by the bolts 41. After this has been accomplished the various letters and spacing blocks are then inserted and the respective 95 plugs 17 and 18 caused to engage the respective sockets 22 and 23. Should it be desired to change the particular wording or arrangement of letters, the letters may be removed and rearranged as desired, by an 100 unskilled person, as all there is to be done is to pull the sign units apart and then reassemble the units in the desired sequence.

What I claim is—

1. A sign structure, comprising a supporting member, a plurality of separable units of insulating material removably engaged on said supporting member, current conducting members carried by each unit, terminals carried by the current conducting 115 members formed at one end with a tongue projecting beyond the unit, and formed at the other end into a socket within the unit for the tongue of the corresponding member of the adjacent unit, whereby the units may 120 be brought into abutting engagement when the terminals of adjacent units are interengaged.

2. The combination of a plurality of lamp and letter units, each formed with a rectan- 125

gular base and having connectors therein, with a supporting structure in the form of a channeled member, the connectors of one unit engaging with the connectors of an adjacent unit.

3. An electric sign comprising a hollow, trough-like support, a plurality of separately formed electrically illuminated letters rising perpendicularly from said support, a plurality of bases there being a base secured to each letter, each base being constructed to seat in said support, and conductors in said bases, the conductors of one base engaging with the conductors of an adjacent base and being adapted to hold said bases in abutting engagement.

4. An electric sign comprising a hollow support, rectangular in cross section, a plurality of separately formed letter units, a plurality of bases, one for each letter unit, means for securing each letter unit in a perpendicular position upon its associated base, said base being constructed to seat in said hollow support, and means for illuminating said letters electrically.

5. An electric sign comprising a support, substantially rectangular in cross section, a plurality of separately formed bases constructed to seat in said support, a plurality of hollow electrically illuminated designs, there being one design rigidly attached to and erected perpendicularly upon each base, and conductors in each base, the conductors of one base engaging with the conductors of an adjacent base and being adapted to hold said bases in abutting engagement.

6. In an electric sign of the class described, a base of insulating material provided with a plurality of longitudinal channels, conducting members fixed within said channels, a hollow, translucent design erected perpendicularly upon the said base, incandescent filaments mounted in the interior of said hollow transparent design and means

providing electric connections between the said incandescent filaments and the conducting members in said base.

7. The combination of a plurality of lamp and letter units, each formed with a base and connectors in said base, with a supporting structure in the form of a channeled member, the adjacent ends of the units adapted for abutting engagement with the connectors of such units interengaged.

8. An electric sign comprising an insulated base provided with a plurality of longitudinal channels, conductor strips located within said channels and projecting at one end as terminals beyond said bases and provided at the other end with sockets within said bases, the terminals of said bases being adapted to interengage in the sockets of adjacent bases, and hollow designs disposed perpendicularly upon the respective bases and connected to the conductor strips for illuminating said designs electrically.

9. An electric sign comprising a base of insulating material, provided with a plurality of channels, conductor strips within said channels, each base including a removable upper plate, a design erected perpendicularly upon each of said plates, and means for connecting the designs with said conductor strips.

10. An electric sign comprising a support, a base including an upper horizontal plate, a perpendicularly disposed design erected on said plate, a plurality of electric filaments within said design, a pair of conductor strips extending through the base beneath said plate, and means for connecting said filaments and said conductor strips.

In testimony whereof I affix my signature in presence of two witnesses.
